CLARENCE F. FISHER, OF DAYTON, OHIO, ASSIGNOR TO THE CRAWFORD, McGREGOR AND CANBY COMPANY, OF DAYTON, OHIO, A CORPORATION OF OHIO.

TOP PLATE FOR LASTS.

Application filed January 10, 1922. Serial No. 528,147.

To all whom it may concern:

Be it known that I, CLARENCE F. FISHER, a citizen of the United States, residing at Dayton, in the county of Montgomery and State of Ohio, have invented certain new and useful Improvements in Top Plates for Lasts, of which the following is a specification:

My invention relates to shoe lasts and more particularly to a reinforcement and protective top plate to be applied to the ankle portion of the last and overlying the usual embedded jack tube or thimble.

The invention contemplates the application to the top of the last of a cover plate of fiber or other non-corrosive pressure resisting material, bearing upon cushion inserts of semi-flexible material at opposite sides of the inserted jack tube or thimble, having a non-yielding pressure resistant bearing upon the end of the jack tube or thimble intermediate such cushion, the overlying portion being of such thickness that the outer end of the jack tube or thimble whether plain or flanged will be inset or embedded to such depth that it cannot possibly come into contact with a shoe lining such overlying protective portion having a hole therein for the jack pin substantially equal in diameter to that of the tube or thimble, but flaring or rounded at its mouth to facilitate the insertion of a jack pin and prevent the pinching of the shoe lining.

The object of the invention is to provide a shoe last wherein the jack tube or thimble will not only be deep seated beyond any possible contact with the lining of a shoe, but wherein the overlying protective body will be sufficiently pressure resistant to enable the shoe heelng operation to be performed upon the last.

It is the common practice when a last is to be used for heelng operation, to provide a metal post or pin therein for reinforcement, which extends through the top cushion of the last ankle, and presents a metal surface which may come in contact with the lining of the shoe, causing it to be disfigured by metallic marks or rust. One of the primary objects of the present invention is to provide a reinforcement and protective top plate of such character and strength that the usual metallic reinforcement post or pin

will be unnecessary, and which will present no surface that will mar or disfigure the shoe lining.

In the manufacture of boots and shoes, it has become quite the practice to apply the heels thereto without removing the wooden last form over which the shoe has been built. This practice conserves labor and time by eliminating the operation of drawing the last preparatory to the heelng operation and relasting the shoe after the heel has been applied. It also improves the production since relasting of the shoe after the heelng operation frequently causes distortion of the upper and sole, resulting in mismated and abnormal shoes. The ordinary wooden last will not withstand the extreme pressure of the heelng machine, necessary to drive at a single blow all of the nails which are to connect the lifts of the heel together and to the sole of the shoe at one time. During the ordinary life of a last it is subjected to this enormous pressure repeatedly a great many times. One of the primary objects of the present invention is to provide a pressure receiving top plate, which will receive the thrust of the heelng operation, and will protect the last heel from splitting or being crushed by the block of the heelng machine. A further object as heretofore pointed out is to insure against injury to the shoe lining by being pinched between the jack pin and the last or being marred or rust marked by coming in contact with metal fittings.

With the above primary and other incidental objects in view as will more fully appear in the specification, the invention consists of the feature of construction, the parts and combinations thereof, and the mode of operation or their equivalents as hereinafter described and set forth in the claims.

Referring to the drawings, Fig. 1 is a side elevation of a shoe last, partly in section, to which the improved construction forming the subject matter hereof has been applied. Fig. 2 is a transverse sectional view of the shoe last embodying the present construction on line 2—2 of Fig. 1. Fig. 3 is a similar view showing the use of a plain jack tube or thimble in lieu of the flanged tube shown in Figs. 1 and 2. Fig. 4 is a

detail perspective view from the under side of the pressure resistant top plate. Fig. 5 is a transverse sectional view of a modification. Fig. 6 is a perspective view of the top plate employed in Fig. 5.

Like parts are indicated by similar characters of reference throughout the several views.

In the accompanying drawings, wherein 10 is shown the preferred, but obviously not necessarily the only form of embodiment of the invention, 1 is an ordinary shoe last, in which is embedded the usual flanged jack tube or thimble 2. In the present instance 15 the top flange 3 of the tube or thimble 2 has been shown countersunk or embedded in the material of the last 1. Mounted upon the top of the ankle portion of the last 1, at opposite sides of the tube or thimble 2 are 20 cushion layers 4 of semi-compressible material such as leather, rubber, super-posed layers of fabric, composition or other like material, possessing a reasonable degree of resiliency. In Fig. 1 these superposed layers 25 of cushion materials 4 have been separated one from the other, fore and aft of the jack tube or thimble 2. Superposed upon these cushion layers 4 is a protective top plate 5, of hard fiber, composition or other non fragile 30 resistant material. This body or top plate 5 is provided with an intermediate lug or boss 6 of like material which projects downwardly intermediate the spaced cushion layers 4, and rests directly upon the top 35 of the last 1, and the flange of the thimble 2. The top plate 5 and cushion layers 4 are of such thickness that the outer end of the thimble 2 is quite deeply seated. The protector plate 5 is provided with a hole 7, through 40 the intermediate downwardly projecting boss or extension 6 which hole 7 is substantially equal in diameter and registers with the bore of the thimble or tube 2. The intermediate portion 6 of the protector plate 45 transmits the pressure direct to the last 1 in direct line with the thimble or tube insert 2, while at either side thereof the top plate is somewhat resiliently supported upon the interposed cushion layers 4. The top of the 50 thimble is sufficiently deep set to insure against the shoe linings ever coming in contact with the metal. The mouth of the hole 7 in this protective plate is flared or rounded outwardly as at 8 to afford a degree of clearance sufficient to prevent pinching of the shoe lining between the jack pin and the protective plate. While the protective plate 5 and dependent bearing lug are preferably 55 formed integral as shown in Figs. 1, 2 and 60 3, they may for convenience and economy of manufacture be separately formed and attached one to the other.

It is the present practice to use both flanged and plain thimbles 2, as shown in 65 Figs. 2 and 3. The present construction is

applicable to lasts employing either style of thimble. In Figs. 5 and 6 there is shown a modification, wherein the bearing lug or pressure transmitting portion 6' is of circular form, comprising substantially a circular hollow boss on the bottom of the protective plate 5, projecting through a like opening in the cushion layer 4, and to a considerable depth within the wooden last body 1, as shown particularly in Fig. 5. In this 70 construction, the fore and aft portions of the cushion layer 4 are interconnected by interconnecting portions of small cross area as shown at 4' in Fig. 5, extending on opposite sides of the pressure transmitting lug 80 6'. The medial lugs or bosses 6 and 6' of the protective plates form piers or non-yielding resistant abutments by which pressure is directly transmitted, while the adjacent portions of the last are protected from the 85 crushing pressure by the yielding or resiliency character of the adjacent cushion layers 4.

From the above description it will be apparent that there is thus provided a device 90 of the character described possessing the particular features of advantage before enumerated as desirable, but which obviously is susceptible of modification in its form, proportions, detail construction and 95 arrangement of parts without departing from the principles involved or sacrificing any of its advantages.

While in order to comply with the statute the invention has been described in language 100 more or less specific as to structural features it is to be understood that the invention is not limited to the specific details shown, but that the means and construction herein disclosed comprises the preferred 105 form of several modes of putting the invention into effect and the invention is therefore claimed in any of its forms or modifications within the legitimate and valid scope of the appended claims.

Having thus described my invention, I claim:

1. A shoe last or the like having a thimble embedded therein characterized by a protective covering overlying the outer end of the thimble comprising a layer of semi-resilient cushion material, and a superposed layer of substantially incompressible material, said superposed layer having a medial projecting bearing area abutting upon the last body and thimble and transmitting direct pressure thereto independently of the interposed cushion layer.

2. A shoe last or the like having a thimble embedded therein, characterized by a body 125 of non metallic, substantially incompressible material overlying the outer end of the thimble and having therein a hole substantially agreeing with the bore of the thimble, the mouth of said hole being flared.

3. A shoe last or the like, having a thimble embedded therein, characterized by a body of hard fiber overlying the end of the thimble and having therein a hole substantially agreeing with the bore of the thimble, the entrance of the hole being rounded inwardly.
4. A shoe last or the like, having a thimble embedded therein characterized by a stratum of cushion material located exteriorly of the end of said thimble and a stratum of substantially incompressible pressure receiving material superposed upon the cushion stratum, and means for transmitting the pressure received by said superposed stratum directly to the last or the like independently of the cushion stratum, said superposed stratum having therein holes substantially agreeing with the bore of the thimble.
5. A shoe last or the like having a thimble embedded therein, characterized by spaced cushion bodies located on opposite sides of the thimble position, and a body of substantially incompressible pressure receiving material overlying the spaced cushion bodies and having direct bearing upon the end of the thimble and adjacent last portion intermediate the cushion bodies.
6. A shoe last or the like, having a thimble embedded therein, characterized by a stratum of cushion material and a superposed stratum of pressure receiving material having a portion thereof projected through the cushion stratum into operative engagement with the last body in proximity to the end of the thimble to transmit the pressure directly thereto.
7. A shoe last or the like having a thimble embedded therein, characterized by a stratum of cushion material and an overlying stratum of pressure receiving material and a pressure resistant pier for said resistant stratum positioned above the embedded tube through which thrust is transmitted to said last body in the vicinity of the thimble, said pier having a hole therein substantially agreeing with the bore of the thimble.
8. A shoe last or the like having a thimble embedded therein, and a superposed body of pressure resistant non-metallic material overlying the end of the thimble and having a hole therein substantially agreeing with the bore of the thimble.
9. A shoe last or the like having therein a deep seated thimble, and a substantially incompressible protective body bearing upon the outer end of said thimble having therein a hole substantially agreeing with the bore of the thimble and bodies of cushion material extending on opposite sides of the thimble, and beneath said protective body.
10. A shoe last or the like having therein a deep seated thimble, and a pressure resistant protective body bearing upon the outer end of said thimble having therein a tapered hole the smaller diameter of which substantially agrees with the bore of the thimble.

In testimony whereof, I have hereunto set my hand this 22nd day of December A. D. 1921.

CLARENCE F. FISHER.

Witness:

H. B. CANBY.
